UNITED STATES PATENT OFFICE.

CHARLES E. GRAHAM, OF SWAMPSCOTT, MASSACHUSETTS, ASSIGNOR TO
GEORGE H. P. FLAGG, TRUSTEE, OF BOSTON, MASSACHUSETTS.

BUFFING OR POLISHING DEVICE.

SPECIFICATION forming part of Letters Patent No. 604,933, dated May 31, 1898.

Application filed December 6, 1897. Serial No. 660,846. (No model.)

To all whom it may concern:

Be it known that I, CHARLES E. GRAHAM, of Swampscott, in the county of Essex and State of Massachusetts, have invented certain new and useful Improvements in Buffing or Polishing Devices, of which the following is a specification.

This invention relates to a yielding-surfaced cylindrical cushion or roll which is supported by a rotary hub or holder and supports a flexible band or working cover, the whole constituting a rotary buffering device or rotary polishing device. An appliance of this character is shown in Letters Patent of the United States No. 590,714, dated September 28, 1897.

The present invention has for its object to provide a centrifugally-maintained yielding-surfaced cylindrical cushion or roll which shall have when in operation a true cylindrical surface of a uniform predetermined diameter and shall also have a yielding quality independent of the centrifugally-actuated portion of the cushion, or, in other words, shall have interposed between the working cover and the centrifugally-actuated portion of the cushion a bed for said cover which will prevent the distortion of the cushion by centrifugal force and will also prevent the outer edge of the cover from forming an undesirable shoulder or projection on the periphery of the roll.

My invention consists in the improvements which I will now proceed to describe and claim.

Of the accompanying drawings, forming a part of this specification, Figure 1 represents a partial side elevation and partial longitudinal section of a roll or cylinder embodying my invention. Fig. 2 represents a section on line 2-2 of Fig. 1. Fig. 3 represents a sectional view of one of the sections of the yielding cushion.

The same letters and numerals of reference indicate the same parts in all the figures.

In the drawings, *a* represents the rigid hub or holder of the yielding cushion, said hub being here shown as a tube adapted to be placed on the shaft which rotates the appliance of which the cushion forms a part. The hub is preferably provided at its ends with suitable means for grasping and supporting

the ends of a flexible working cover *b*, which may be a sheet of sand or emery paper, the same means being here shown that are set forth in Letters Patent of the United States No. 550,062—namely, collars *g*, *g*, of felt or other suitable yielding material, affixed to the hub, and clamping-fingers *h*, which project over the peripheries of said collars and are adjustably connected with the hub, so that they may be forced inwardly upon the end portions of the cover, pressing the latter into the yielding surfaces of the collars *g*. My present improvements are not dependent on these particular devices and may be used in connection with any other suitable means for connecting the end portions of the working cover with the hub *a* or, without such means.

The hub is provided with a centrifugally-maintained yielding cushion, here shown as composed of a series of annular flexible or limp sections *i* strung upon the hub *a*, their outer edges constituting a series of flexible or limp cover-bearings surrounding the hub and adapted to yield at all points. The said sections are preferably composed of limp or flabby leather having comparatively little inherent stiffness, kid, sheepskin, and other similar kinds of leather being suitable.

It is essential that the sections be spaced or separated to give the bearing edge of each section freedom to sway or bend sidewise to some extent, this freedom also enabling the bearing edges to sink inwardly toward the hub.

Each section may be composed of two or more annular flexible disks or members *3*, *3*, said members being cemented or otherwise firmly secured together at their inner portions, while their outer portions are disconnected and separable.

To secure adequate spacing between the sections, spacing-pieces *4* are provided, which are preferably rings or washers of leather-board or other comparatively stiff material, one of these being preferably cemented or otherwise secured to each section. The sections thus constructed are adapted to be assembled upon the hub to form a cushion of any desired length, the cushion being made more or less yielding by decreasing or increasing the number of sections.

The marginal portions of the sections are preferably weakened to make the bearing edges more yielding. This is best accomplished by cutting out small pieces of the material, and forming slots 5 in the flexible portions of the sections.

When the cushion is rapidly rotated, the bearing edges of the sections are yieldingly held by centrifugal force at their maximum distance from the axis of rotation. The spaces between the sections permit the bearing edges to sink under the pressure of the work against the working cover *b* sufficiently to conform to the inequalities and curves of the work.

The construction above described is practically the same as that set forth in Letters Patent No. 500,714, above referred to.

Heretofore the working cover *b* has been in direct contact with the margins of the disks. When the roll is rotated at a high rate of speed, the edges of the disks become the equivalent of springs, which while adapted to yield inwardly are pressed outwardly with considerable force. This outward pressure sometimes causes distortion of the roll, because the loose or more yielding portions of the edges of the disks are forced outwardly farther than the firmer portions. The outward pressure also causes the overlapping end of the cover *b* to form an objectionable shoulder on the cover by preventing the inward sinking of said end and of the end which it overlaps. To overcome these objections is the chief object of my invention, and to this end I interpose between the centrifugally-maintained cushion and the working cover *b* a seamless tubular woven sheath *s*, which incloses the cushion and is laterally inelastic, or, in other words, is not capable of stretching in the direction required to increase its diameter, so that the edges of the disks are prevented from being forced outwardly beyond the internal diameter of the sheath. The fabric of which said sheath is made is, however, compressible and of such thickness that it forms a bed for the working cover which is sufficiently yielding to permit the overlapping edge of the cover *b* and the edge which it overlaps to sink inwardly, as shown in Fig. 2, and thus prevent the formation of a projecting shoulder.

The seamless tubular woven fabric of the sheath is preferably similar to ordinary tubular wicking for lamps, the warp and weft threads being preferably of cotton. The lateral inelasticity of the sheath or its freedom from liability to stretch in the direction required to increase the diameter of the sheath is an important feature, this quality preventing the fabric from being stretched by the outward pressure of the centrifugally-main-

tained cushion against it, and thus permitting the distortion of the cushion, and from losing the compressibility necessary to permit the sinking of the edges of the working cover. The seamless construction of the sheath is also important, because the sheath is thereby caused to present a surface which is uniformly compressible at all points and free from a relatively hard ridge or line which would necessarily be presented if two edges of a covering-piece were united to form a seam or joint. In an appliance of this character such a seam or joint would be very objectionable and would prevent the work from being uniformly buffed or finished, the relatively hard part at the seam giving a harder pressure on the work than the other portions. The predetermined diameter of the sheath should be such that the sheath will be filled and held in a plump condition by the cushion when the latter is centrifugally distended, the flexibility of the sheath being such that it yields with the cushion to the pressure of the article applied to the cover.

The sheath may be held in place on the cushion by the fingers *h*, which secure the working cover. I prefer to cover the ends of the sheath with finishing-caps *s'*, preferably of leather, cemented to the ends of the sheath and turned inwardly beyond said ends and clamped between the collars *g* and the plates or heads *h'*, in which the fingers *h* are guided.

It is obvious that my improvement may be applied to a centrifugally-maintained cushion of any other suitable construction.

I claim—

1. An appliance of the character specified, comprising a rotary hub, a yielding cushion secured to said hub and adapted to be centrifugally maintained, and a seamless tubular laterally-inelastic sheath of fibrous material having a compressible body inclosing said cushion and forming a yielding bed for a working cover.

2. An appliance of the character specified, comprising a rotary hub, a cushion composed of limp annular sections surrounding the hub and closely confined at their inner portions around the hub, their outer portions being free to yield, and a seamless tubular laterally-inelastic sheath of fibrous material having a compressible body inclosing said cushion and forming a yielding bed for a working cover.

In testimony whereof I have signed my name to this specification, in the presence of two subscribing witnesses, this 23d day of November, A. D. 1897.

CHARLES E. GRAHAM.
